(57) **CLAIM**

The ornamental design for automatically guided vehicle, as shown and described.

DESCRIPTION

FIG. 1 is a front view of an automatically guided vehicle showing our new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a first front perspective view hereof;

FIG. 8 is a second front perspective view thereof;

FIG. 9 is a first rear perspective view thereof; and,

FIG. 10 is a second rear perspective view thereof.

The broken lines in the views show portions of the automatically guided vehicle that form no part of the claimed design.

1 Claim, 10 Drawing Sheets
